SANITARY TOOTH BRUSH CONTAINER
WITH ANTISEPTIC VIAL

John F. Bell, Cape May Court House, N. J.

Application April 11, 1936, Serial No. 73,956

6 Claims. (Cl. 206—15.1)

The invention relates to a sanitary tooth-brush container with antiseptic vial.

The object of the invention is to provide, in a manner as hereinafter set forth, a means for suspending a tooth-brush by its head, within which means, while the tooth-brush is so suspended, the tooth-brush head will be subjected to a thorough sterilization, the purpose being to have the tooth-brush head sterilized before each time it is used.

Further objects of the invention are to provide, in a manner as hereinafter set forth, a sanitary tooth-brush container or holder which is simple in its construction and arrangement, strong, durable, compact, thoroughly efficient in its use, conveniently operated to permit of the suspension thereby and the removal therefrom of the brush, and comparatively inexpensive to manufacture.

With the foregoing and other objects which may hereinafter appear, the invention consists of the novel construction, combination and arrangement of parts as will be more specifically described and are as illustrated in the accompanying drawing wherein is shown an embodiment of the invention, but it is to be understood that changes, variations and modifications may be resorted to which fall within the scope of the invention as claimed.

In the drawing:

Figure 1 is a vertical sectional view of the holder.

Figure 2 is a front elevation of the holder when closed.

Figure 3 is a section on line 3—3, Figure 1.

Figure 4 is a section on line 4—4, Figure 1.

Figure 5 is a fragmentary view in vertical section on line 5—5, Figure 3.

Figure 6 is a top plan view of the holder and its support, and

Figure 7 is a top plan view of a series of holders fixed to a common support.

The holder is of cylindrical contour and includes an annular split, outer, vertical shell 8. The split in the latter is at the front thereof. The edges of the split of shell 8 are arranged a desired distance apart to form an opening for the entrance of the head of the brush 10, indicated in dotted lines Figure 5, into the shell. The latter is open at its top and bottom. One of the edges of the split is formed with an inwardly extending hook 9. The other edges 9a of the split are squared throughout. Positioned within the shell 8 and coacting with the inner face at the lower portion of the latter is a pair of track forming members 11, 12 of segmental contour

and oppositely disposed with respect to each other. The member 11 is of greater length than the member 12. Each of said members is open at its outer end and of angle shape in vertical section. Each member includes a lower, vertical leg 13, an intermediate horizontal leg 14 and an upper vertical leg 15. The leg 14 extends inwardly from the upper end of the leg 13 and merges at its inner end into the lower end of the leg 15. The legs 15 of said members 11, 12 are offset with respect to the inner face of shell 8, and provide in connection with the latter a pair of trackways and with the outer end of one track way aligning in spaced relation with the outer end of the other track way. The track-ways are opened at their forward or outer ends and closed at their rear ends by the flanges 16 extending from the legs 15 and abutting or secured to the inner face of the shell 8. The legs 15 of the members 11, 12 extend beyond the hook 9 and edge 9a of the split at the front of the shell 8. The flanges 16 constitute stops for a purpose to be referred to.

The opening provided by the split at the front of the shell 8 is closed by a spring controlled shutter structure 17 formed of a shutter 18 of segmental contour in plan which seats upon the legs 14 and bears against the outer face of the legs 15. The shutter 18 at its sides is formed with forwardly directed hooks 19, 20 which coact respectively with the hook 9 and edge 9a for arresting the closing movement of the shutter to retain the latter in closed position against the action of the controlling spring for structure 17. Formed integral with the upper end of the shutter 18 is a triangular shaped slide 21 of segmental contour in cross section. Fixedly secured to the slide 21 is a rotatable stub shaft 22 which depends below slide 21 and carries a radially disposed pin 23 to which is anchored the end 24 of a controlling spring 25. The other end of spring 25 is connected to a bracket 26 secured to the inner face of the shell 8 in proximity to its upper end. The shaft 23 is disposed vertically and carries on its upper end a finger piece or knob 27 to facilitate the turning of the shaft when occasion requires. The shaft is turned against the action of the spring 25 for the purpose of opening the shell 8 so access can be had to the interior of the holder. The shutter 18 is of a width to close the open front of shell 8 normally and when shutter 18 is shifted from its normal position it is moved into the member 11 the desired extent to permit entrance to the holder. The opening movement of the shutter 18 is limited by the hook 19 coacting with the stop 16 on the member 11. The shutter

18 when moved in either direction travels in the track forming members 11, 12.

Mounted on the upper end of the shell 8, and closing the top of the latter is a cap 28 formed with an opening 29 for the passage of shaft 22. The slide 21 is positioned against the inner face of the cap 28. The latter is formed with a rim 30 which is secured to the outer periphery of the shell 8 at the upper end of the latter.

10 The lower end of the shell 8 is closed by a cup-shaped member 31 which depends from and is secured to shell 8. Member 31 consists of an annular part 32 and a lower part 33 of segmental cross section integral with the lower end of the 15 part 32. The lower part 33 diametrically thereof is provided with a cutout 35 formed in the front of the upper part 32. The cutout 34 extends from the front of the lower part 33 to a point between its axis and its rear edge. The 20 upper part 32 of the member 31 is fixedly secured to the outer periphery of the shell 8.

Formed integral with the rear of the inner face of the shell 8, in proximity to the lower end of the latter and disposed in alignment with the cutout 35 is an upstanding L-shaped retainer 36 extending forwardly with respect to the rear of the shell 8 and having its lower portion formed with a resilient vertically disposed short front arm 37. The retainer includes a vertical rear arm 37a of greater length than, spaced from and having its lower portion disposed parallel to the arm 37. The latter is formed integral with a resilient suspension clip 38 for and into which is adapted to be positioned an intermediate part 35 of the handle of the brush when the latter is in suspended position, as shown in dotted lines in Figure 5. Formed integral with, extended forwardly from the arm 37a and forming an element of the retainer 36 is a spring clip 39. The retainer 40 is employed for detachably suspending an oval receptacle 40 within the shell 8 at the rear thereof. Arranged in the receptacle is a sterilizing medium 41 and an absorbing body 42 positioned above the medium 41. Body 42 constitutes a wick and it is exposed through a slot 42a lengthwise of the receptacle 40. When the brush is suspended from the holder, the slot 42a opposes the back of the head of the brush. Positioned in the member 31 and below the bottom edge of the shell 8 is a pair of resilient members 43, 43a of any suitable material, preferably sponge rubber. The members 43, 43a normally extend across the cutouts 34, 35 and act when in normal position as closures for said cutouts and as grippers for the brush handle.

With reference to Figure 6 a suspension for the holder is indicated at 44 and which includes means indicated at 45 for attaching to each side of the holder. The suspension is adapted to be 60 anchored to a suitable support.

With reference to Figure 7 a suspension is indicated at 46 for a series of abutting holders and said suspension includes means as at 47 for connection to the outer holders of the series. The 65 suspension 46 is adapted to be anchored to a suitable support. Preferably a suspension will be secured to the shell 8 intermediate the ends of the latter and in this connection, attention is directed to Figure 2 which illustrates the suspension 70 44.

It will be assumed that the holder is in the position shown in Figure 3 and it is desired to remove the brush. The shutter structure 17 is shifted in the direction to the left of Figure 3 thereby opening the front of the shell 8, to permit

of the passage from the holder of the brush head when the brush is removed by grasping the brush handle below the shell 8. When the brush is removed, the shaft 22 is released and the shutter device or structure automatically returns to the 5 position shown in Figure 3. When it is desired to suspend the brush from the holder, the shutter device is again shifted to open position and the brush forced into the holder between the members 43, 43a to an extent to mount the neck of 10 the handle of the brush on the top edge of the spring clip 39 and with the handle depending from the member 31. When the shaft 32 is relieved of manual pressure, the shutter device 15 automatically closes the holder. When the brush is in the position just referred to, its head is subjected to the action of the sterilizing medium.

What I claim is:

1. In a sanitary holder for suspending a tooth brush and sterilizing the head of the latter and 20 of that type including an open front sterilizing medium container, said holder including a hollow element for enclosing such receptacle and the head of the tooth brush, and a suspension including means for supporting the receptacle 25 and means for positioning the head forwardly of and in proximity to the open front of the receptacle, said means for supporting the receptacle being secured to the inner face of said element, said means for positioning the brush 30 head forwardly of the receptacle extended forwardly from the lower portion of the means for supporting the receptacle.

2. In a sanitary tooth brush holder, an upstanding cylinder split from end to end of its 35 front and having the edges of the split in permanent spaced relation, shiftable means within said cylinder for normally closing the space between said edges, said cylinder being opened at its upper and lower ends, an upper structure 40 secured to the cylinder for permanently closing the upper end of the latter and through which extends a part of said means, a support for removably suspending the head of a tooth brush within and with the handle of the brush depending 45 through the lower end of the cylinder, and a lower structure encompassing, secured to and depending from the lower portion of said cylinder, said lower structure having its front and bottom slotted and being provided therein with compressible 50 and extendible normally abutting elements for the passage therebetween of said handle, said elements permanently abutting the bottom edge of the cylinder for normally closing the lower end of the latter and for normally closing said bottom slot and that portion of the front slot of said lower structure depending below said bottom edge.

3. In a combined tooth brush holder and sterilizing structure of that type including a normally closed receptacle having a means to permit the positioning of the tooth brush therein, the combination of a vertical arm adapted to be secured to the inner face of the receptacle, a forwardly extending bottom arm disposed at right angles 65 to and integral at its rear end with the lower end of the vertical arm, a vertical front arm disposed in parallel spaced relation to and of less length than said rear arm, said front arm being integral at its lower end with the forward end of the lower arm, a spring clip extending from the upper portion of said rear arm and providing in connection with the said arms for suspending an open front container carrying a sterilizing medium, and a spring clip extending forwardly from 70 75

said front arm and providing means for suspending the head of the tooth brush forwardly of and in proximity to the open front of the container.

4. In a sanitary holder for tooth brushes, a normally closed open front container structure, holding means for the tooth brush arranged within and fixed to said structure, said structure being provided therein at the lower portion thereof with a pair of spaced endwise aligning tracks, a spring controlled shiftable shutter travelling on said tracks for normally closing the open front of said structure, one of said tracks being provided with a stop for limiting the opening movement of the shutter, said structure and shutter having a coating means for limiting the closing movement of the shutter, and shiftable means connected to the shutter, arranged within and extended from said structure for shifting the shutter to open position against the action of the controlling spring for the shutter.

5. In a sanitary holder for sterilizing tooth brush heads, an upstanding suspension common to an open front container carrying a sterilizing

medium end to the head of the tooth brush, said suspension including means at its bottom for supporting the container, means at its upper end for connecting the container thereto and means forwardly of the means for supporting the container for suspending the brush head forwardly of, parallel to and in close proximity to the open front of the container.

6. In a sanitary holder for tooth brushes, a normally closed open front container structure for receiving the tooth brush, said structure including shiftable means arranged therein for opening its front, said structure including an upper closure means therefor through which a part of said shiftable means extends, and said structure including a lower closure means therefor, said lower closure means being provided with a slot for passage of the handle of the tooth brush into and out of said structure, and said lower closure means including normally abutting resilient elements for gripping the handle.

JOHN F. BELL.
